BUCKLE OR SIMILAR ARTICLE

Vincent De Liso, Astoria, Long Island, N. Y.

Application November 20, 1937, Serial No. 175,625
Renewed March 14, 1940

1 Claim. (Cl. 24—69)

This invention relates to a buckle or tongue fastener for use on shoes, coats, dresses or other articles of wearing apparel.

It is an object of this invention to produce a buckle or fastener which is ornamental and yet highly efficient in operation, and at the same time is cheap to construct.

It is a further object of this invention to provide a buckle which does not give discomfort to the wearer, even where the same is subjected to relatively high stresses, such as, for example, in ladies' shoes.

And it is a further object of this invention to provide a buckle having a tongue which is adapted to engage an eyelet, which tongue, when in the opened position, is held substantially vertical to facilitate the insertion of the same thru the eyelet.

These and other objects of the invention will be readily apparent to those skilled in the art from the following description taken in conjunction with the accompanying drawing, in which:

Fig. 1 is a perspective view of a lady's shoe provided with a buckle constructed in accordance with the present invention.

Figs. 2 and 2A are perspective views of my buckle in closed and open positions respectively.

Fig. 3 is an exploded view of the buckle shown in Fig. 2, showing in detail the parts thereof.

Figs. 3A and 3B are detail views.

Figs. 4 and 4A are perspective views of a modification shown in closed and open positions respectively.

Fig. 5 is an exploded view of the buckle shown in Fig. 4.

Fig. 5A is a detail view.

Referring in detail to the drawing the buckle or clasp 10 is seen to comprise a base plate 11 stamped out of sheet steel in the shape shown in Fig. 3A. During the stamping operation the holes 12 are punched thru to permit the buckle to be sewed or otherwise attached to the shoe or article upon which the same is used. Arms 13 have protrusions or tits 14 punched therein, which act as the pivotal support for the tongue 30 as will be more fully described below. The tits are punched thru in such a way that the bent-in fragments of the metal act as an axis for 20, thus avoiding the necessity of using separate pivoting axes.

The plate is now pressed into the form shown in Figs. 2 and 3, with the arch 15 formed therein, and the arms 13 turned up at right angles to the plane of the plate 11.

A flat steel spring member 20, shaped as shown,

and having an arched curvature longitudinally thereof is placed on top of the plate 11. The curvature of 20 is greater than that of the arch 15 so that the spring action is had in depressing 20 to contact throughout with 15. Holes 21 are cut in the spring 20 to render the same sufficiently yieldable, while at the same time permitting the use of a heavy enough steel so that the spring will not crack or break during continued use. The recess 22 is formed in the spring 20 so that while the same lies on the plate 11 without being attached thereto, yet it is held in place by the arms 13 and the tongue 30.

Carried by the arms 13 is a tongue 30, which is provided with recesses 31 shaped to receive the tits 14 on the arms 13, thus providing a pivotal mounting for the tongue. The tongue consists of a head portion 32 and a tail 33. Since the tail portion of the buckle is substantially the only part of the device which is visible when in use, the tongue is preferably die cast of steel, and polished off to present an ornamental appearance. The bottom face 34 of the portion 32 is preferably flat so that when the tail is depressed the action of the spring 20 presses up against said face and holds the tongue in the closed position. The surface 35, which contacts the spring 20 when the tail is raised up to open the buckle, is shaped with a flat area 36 adjacent to the surface 35, which area merges into a curved area as shown. This enables the tongue to be easily pivoted about 31 after the tail is raised to open the buckle; and the flat area of this surface in cooperation with the spring 20 causes the tail to remain in vertical position when the tail is pivoted upwardly sufficiently to pass the surface 34 out of contact with 20, and the flat edge of 35 into contact with 20.

It will be understood that in the use of this device, that once the tail is depressed until the flat face 34 snaps into contact with the spring 20, no matter how great the tension might be on the device, the same will not open, but will tend to remain even more firmly closed. This result follows from the fact that the stress due to such tension acts below the fulcrum 31 and serves to lock the tongue. However, when it is desired to open the device, it is very easy to do so due to the mechanical advantage of the lever arm 33.

In a device such as this, it is highly desirable that the tail be held in a vertical position when the buckle is open, to facilitate the insertion of the tail 33 thru an eyelet or hole 37 in the article being buckled. As already explained above

this desideratum is realized by virtue of the cooperation between 35 and 20.

The assembling of the present device is extremely easy and inexpensive due to the fact that the spring 20 is unattached, it being merely held by the slots 22 which receive the arms 13. The only actual physical union of the parts is in forcing the tits 14 into the depressions 31.

In order to provide a buckle which has the utilitarian features of the foregoing device, but in which it is tolerable to sacrifice the fineness and ornamental qualities of the same in the interests of economy, I have provided a modification which is made entirely of stampings of sheet metal, no die castings being used. Referring particularly to Figs. 4-5, the buckle 40 comprises a base plate 41 stamped out in the form shown in Fig. 5A with the prongs 42 and 43. Tits 44 are formed on prong 43. The prong 43 is turned up in the curved position.

The tongue 50 having integrally formed ears 51 provided with holes 52 to receive the tits 44 is first stamped out of a flat piece of sheet metal and then bent into the form shown. A flat spring 60 is riveted or otherwise attached to the tail 53 at 61.

When the buckle is assembled, the tits 44 engage the holes 52 and the flat spring 60 rides on the edge 45 of the prong 43.

When the buckle is closed the spring contacts the edge 45, thus tending to pivot the tail 53 in a clock-wise direction about the fulcrum 43. As explained above in connection with the other modification when the buckle is fastened the strain of the parts being held together by the buckle tend to hold it locked.

Now, when the tail 53 is raised to open the buckle the flat spring rides over the edge 45 and further upward motion of 53 causes the edge 40 of 60 to ride underneath 45 and abut against the vertical part of 43. When 53 is at right angles to 41, the edge of the spring 60 strikes the prong 43. Between this force and the force necessary to pull the spring over the edge 45 in the closing action of the buckle, the tail 53 is held in the vertical position. The need for this has already been set forth above.

In the actual use of this buckle, especially in

ladies' shoes where substantial stress is placed on the parts buckled together, it will be seen that there is practically no component of the force placed on the buckle, which acts at right angles to the plane of the base plate. In other words there is practically no force acting to press the buckle against the wearer's foot. I have found in practice that in a shoe provided with this buckle there is no discomfort due to the presence of the buckle, no matter how sensitive the spot of the foot at which the buckle is mounted. The forces acting on the buckle are for the most part in the plane of the base plate and so close to the base plate that there is practically no turning movement about the plate. In so far as I am aware, I am the first to provide a highly ornamental buckle of this kind which can be used as herein described.

Obviously, many changes in the specific embodiments disclosed herein will readily suggest themselves to those skilled in the art, and I do not, therefore, intend to be limited in the scope of this invention except as defined in the appended claim.

Having thus described my invention, I desire to claim and secure by Letters Patent of the United States:

A buckle of the character described comprising a base plate having apertures at the opposite edges thereof for attachment of said plate to the article to be provided with the buckle, said plate having an upwardly curved portion between said opposite edges, a pair of upwardly extending arms at the opposite side edges of said plate substantially at the center thereof between said opposite edges, a flat upwardly bowed spring disposed over said upper surface of the plate between said arms and having a greater curvature than said curved plate portion, and a tongue pivotally mounted at one end thereof on and between said arms and having an extension at its said end provided with a relatively broad end surface engageable with said spring centrally of the latter for releasably holding the tongue in closed position, said connection of the tongue centrally of the plate causing the pressure of said tongue on said plate to equalize thereon.

VINCENT DE LISO.
